W. P. ALBERT

CONTROLLING SYSTEM

Filed June 20, 1922

Inventor:
Walter P. Albert
by
W. Beatty, ATTY.

UNITED STATES PATENT OFFICE.

WALTER P. ALBERT, OF EAST ORANGE, NEW JERSEY, ASSIGNOR TO WESTERN ELECTRIC COMPANY, INCORPORATED, OF NEW YORK, N. Y., A CORPORATION OF NEW YORK.

CONTROLLING SYSTEM.

Application filed June 20, 1922. Serial No. 569,682.

To all whom it may concern:

Be it known that I, WALTER P. ALBERT, a citizen of the United States, residing at East Orange, in the county of Essex, State 5 of New Jersey, have invented certain new and useful Improvements in Controlling Systems, of which the following is a full, clear, concise, and exact description.

This invention relates to electrical control 10 devices and more especially to devices of this character when adapted for use in telephone and similar systems.

The object of the invention is a control 15 system in which an operating and controlling relay is actuated in response to local currents induced or created by changes of current in a line circuit.

A feature of the invention relates to the 20 provision, in a system where variably operable switches or similar devices are actuated by a control relay, of local circuits each including a winding of said relay in which currents are induced to operate such relay by each change of current in the line circuit.

25 A still further feature relates to the provision of means for holding the control relay operated, after it has responded to a momentarily induced current, until the switch or device under the control of such relay has made a complete operation.

These and other features contemplated by the present invention will become more apparent from the following detailed description and also from the appended claims.

35 In the drawing an electrical control mechanism embodying the principles of this invention is illustrated as incorporated in a telephone system. In its broadest aspect it is to be understood that controlling 40 mechanisms of this character may be applied to a wide variety of uses. In the present instance, however, it is shown as adapted for receiving current impulses transmitted over a subscriber's telephone line to the central office and in turn for delivering these impulses to a registering or recording equipment.

The drawing illustrates a portion of a subscriber's telephone line 102, 103 entering 50 a central office. In any well known manner this line is extended through a line finder or a line switch either to a trunk leading to a selector switch or to an operator's position as desired. Inasmuch as the means for extending the subscriber's line forms no es-

sential part of this invention, the same has not been shown.

Since it is desirable to take a record of the impulses transmitted over the line, there is provided at the central office an impulse receiving and registering apparatus. This registering mechanism comprises among other elements a plurality of relays 106, 108 and 111 which receive the incoming impulses and deliver them to the registers. 60 There may be any desired number of registers for receiving the impulse series and also these registers may be of any suitable form. Two registers 110 and 115 are shown, each consisting of a step-by-step switch 70 driven by a stepping magnet 124 or 125. As many other registers as are needed may obviously be provided.

In addition to the registers a control 75 switch 120 is employed for associating the impulse receiving relays in succession with the several register switches so that as soon as one series of impulses is recorded on a given register the next series may be recorded on the succeeding register. 80

It is sometimes desirable to provide a plurality of these impulse receiving and recording mechanisms at the central office, any one of which may be associated with a subscriber's line. To this end a selecting 85 switch, the brushes 104 and 105 of which are illustrated, is employed for finding an idle mechanism.

A detail description will now be given 90 of the manner in which the system operates. When the subscriber of line 100 initiates a call, the line is extended through the brushes 104 and 105 of the selector switch to an idle impulse receiving and recording mechanism. A circuit may thereupon be traced 95 from battery, through the left-hand winding of relay 108, brush 105, conductor 103, over the loop of the calling line and returning by way of conductor 102, brush 104, through the left-hand winding of the balancing coil 107 to ground. Current flowing in this circuit energizes the left-hand winding of relay 108 and also sets up a flux in the left-hand winding of the balancing coil 107. A circuit also may be 105 traced from battery, through the left-hand winding of relay 108, condenser 109, left-hand winding of relay 106, left-hand winding of coil 107 to ground. The potential across the terminals of the condenser 110

is reduced by the shunting action of the circuit traced including the line. Another circuit may be traced from battery, through the right-hand winding of relay 108, middle winding of relay 106, conductor 131, brush 112 of the control switch 120, terminal 113, contact of magnet 124, conductor 130, winding of relay 121, brush 116, terminal 117, condenser 126, resistance 127 to ground. The potential applied across the terminals of condenser 126 in the circuit just traced and also through the winding of magnet 124 builds up a charge in said condenser. The relay 106, however, remains inert since sufficient current does not pass through the windings of said relay to cause the operation thereof. Relay 108 becomes energized through its left-hand winding and closes a circuit for the relay 111 which also operates.

When the subscriber manipulates his dial 101 to send a series of impulses, the line circuit is opened at the first interruption of the contacts of the said dial. Immediately that the line circuit opens, the flow of current through the left-hand winding of relay 108 and the left-hand winding of coil 107 ceases and the magnetic flux built up in these windings collapses. The collapse of the flux in the windings of relay 108 and coil 107 according to well known laws induces a high potential which creates a momentary flow of current. Since the line is open the current of self-induction cannot flow therein and, the shunt of the line being removed from the condenser 109, the potential of battery applied across the condenser 109 through the left-hand windings of relays 108, 106 and 107 aids the potential of self-induction to produce a charge on the condenser. This charging potential causes current to flow through the left-hand winding of relay 106.

Likewise the collapse of flux at the relay 108 induces a momentary potential in the right-hand winding thereof. Since the condenser 126 is already charged to battery potential, the added higher potential of self-induction is sufficient to increase the charge on the said condenser, causing a momentary flow of current through the middle winding of relay 106. The combined flow of current through the left-hand and middle windings of relay 106 is sufficient to cause said relay to attract its armature. Immediately that the relay 106 operates a circuit is closed from battery, through the right-hand winding of relay 108, middle winding of relay 106, contact of relay 106, contact of relay 111, to ground. Relay 106 locks in this circuit and is held by the steady flow of current after the momentary current of self-induction dies away. Upon the operation of relay 106, a circuit is established from ground through the contact of relay 111, contact of relay 106, right-hand winding of relay 106, con-

ductor 130, winding of slow-to-release relay 121, brush 116, terminal 117, winding of stepping magnet 124, to battery. At the same time a circuit is also closed from ground through the contact of relay 111, contact of relay 106, conductor 131, brush 112, terminal 113, contact of magnet 124, winding of relay 121, brush 116, terminal 117, winding of stepping magnet 124 to battery. It will be noted that the circuit last traced is in shunt of the previously traced circuit through the right-hand winding of relay 106. The stepping magnet 124 becomes energized in this circuit and when deenergized advances the brush 122 and such other brushes as may be associated with the register 110. When the armature of the register magnet 124 has taken a full forward step, the contact of said magnet opens. The opening of the contact of magnet 124 removes the shunt around the right-hand winding of relay 106, whereupon this right-hand winding is included directly in series with the winding of stepping magnet 124 and becomes fully energized.

The right-hand winding of relay 106 is wound in a differential relation with the other windings of said relay. Hence, when said right-hand winding is fully energized it differentiates the effect of the middle winding, and the relay in consequence releases its armature. The release of relay 106 opens the circuit of stepping magnet 124 and the latter becomes deenergized.

Relay 121, upon energizing, closes a circuit for the stepping magnet 119 of the control switch 120. Magnet 119 operates and prepares to advance the brushes 112, 116, 133, etc. from the first position to the second position. This switch is so constructed that the brushes are not moved forward until the stepping magnet deenergizes.

In the meantime, the subscriber's line is closed at the end of the first interruption and the circuit through the left-hand winding of relay 108 and the left-hand winding of coil 107 is reestablished. Hence, relay 108 remains energized from one interruption to the next, assuming that the subscriber's line closes before the relay 106 has time to deenergize on the preceding interruption. Should, however, the relay 106 become differentiated and release to open the circuit through the right-hand winding of relay 108 prior to the closure of the subscriber's line at the end of the impulse, relay 108 would become deenergized. Relay 111, however, being slow to release, holds its armature attracted during interruptions. This is immaterial, however, since immediately that the line is closed at the next interruption, relay 108 again becomes operated ready to exercise its control when the dial opens the line.

For each impulse transmitted, the above

series of operations occur and the magnet 124 advances the brushes of the register switch 110 from position to position. During the series of interruptions, slow-to-release relay 121 remains energized to hold the circuit of magnet 119 closed. At the termination of the first series, a sufficient interval elapses to permit the deenergization of relay 121. This relay opens the circuit 5 of magnet 119, which in turn, releases to advance the brushes 112, 116, etc. of the control switch 120 on to their second position terminals.

With the subscriber's line closed preparatory to sending the second series of interruptions, the circuit previously traced through the left-hand winding of relay 108 and the left-hand winding of coil 107 is established and the condenser 109 is shunted and 10 charged as explained. With the control switch 120, however, in position 2, the following circuit is established: battery, through the right-hand winding of relay 108, middle winding of relay 106, conductor 131, brush 112, terminal 114, contact of magnet 125 of the second register 115, conductor 130, winding of relay 121, brush 116, terminal 118, condenser 128, resistance 129 to ground. The condenser 128 is charged in 20 this circuit.

For each interruption of the second series the relay 106 is operated by a momentary current induced in the circuits including its left-hand and middle windings, respectively, 25 and an impulse is delivered to the stepping magnet 125 of the second register switch 115. At the end of the second set of interruptions when the switch 115 has been set to the corresponding position, relay 121 becomes deenergized and the stepping magnet 119 advances the control switch to its third 30 position.

In a similar manner as many succeeding register switches or similar devices as necessary may be operated.

When it is desired to release the registers the line is opened permanently and relay 108 releases for a sufficient interval to permit relay 111 to retract its armature. 40 Relay 111 closes a circuit through its contact, brush 133 and the associated terminals, contact and winding of magnet 119 to battery. Magnet 119 interrupts its own circuit and advances the brushes to the releasing 45 position where the registers 110, 115 may be restored in any well known manner.

What is claimed is:

1. The combination with a line circuit having a source of current therein, of a plurality of other circuits, a relay having a winding in each of said other circuits, means for changing the flow of current in said line circuit, the change of current in said line circuit inducing a flow of current in each 50 of said other circuits, said relay responding

to the current induced in said other circuits, and a variable operable device actuated by said relay.

2. The combination with a line circuit and a source of current therein, of a number 70 of other circuits, a relay having a separate winding associated with each of said other circuits, means for repeatedly opening and closing said line circuit, the change of current in said line circuit caused by each 75 opening thereof inducing a flow of current in each of said other circuits, said relay responsive to the flow of current induced in said other circuits, and a variably operable switch actuated at each operation of said 80 relay.

3. The combination with a line circuit having a source of current therein, of a plurality of other circuits, a relay having a plurality of windings, one included in each 85 of said other circuits, means for changing the flow of current in said line circuit, the change of current in the line circuit inducing a momentary flow of current in said other circuits, said relay responding to the 90 flow of current induced in said other circuits, means for maintaining said relay operated after the momentary current ceases to flow, and a variably operable device actuated by said relay. 95

4. The combination with a circuit having a source of current therein, of a second circuit, a relay having a winding in said second circuit, a condenser in said second circuit, means for altering the flow of current 100 in said first circuit, the change of current in said first circuit inducing a current in said second circuit which charges the condenser and flows through said winding, said relay responding to said induced current, and 105 means controlled by said relay.

5. The combination with a line circuit having a source of current therein, of a second circuit, a relay having a winding in said second circuit, a condenser in said second 110 circuit arranged to be charged by the source of current in said line, means for changing the flow of current in said line, the change of current in the line circuit inducing a current in said second circuit which charges the 115 condenser and flows through said winding, said relay responding to the induced current, and a variably operable switch actuated by said relay.

6. The combination with a line circuit having a source of current therein, of a plurality of other circuits, a relay having a winding associated with each of said other circuits, a condenser in each of said other circuits, said condensers arranged to be charged by the source of current in said line circuit, means for changing the flow of current in said line, the change of current in said line circuit inducing a current in each 120 of said other circuits which charges the 125 re- 130

spective condensers and flows through the corresponding windings of said relay, and a variably operable device actuated by said relay.

5 7. The combination with a line circuit having a source of current therein, of a second circuit, means for changing the flow of current in said line circuit, the change of current in said line circuit inducing a momentary flow of current in said second circuit, a relay responsive to the current induced in said second circuit, a progressively operable device actuated on each operation of said relay, and means for holding said relay operated until said device has completed its operation.

8. The combination with a line circuit having a source of current therein, of a second circuit, a relay having a winding in said second circuit, means for repeatedly opening and closing the line circuit, the change of current in said line circuit due to each opening thereof inducing a momentary flow of current in said second circuit, said relay 20 responding to each momentary flow of current in said second circuit, a progressively operable switch actuated at each operation of said relay, and means for maintaining the operation of said relay until said switch has 25 taken a full operation.

9. The combination with a line circuit having a source of current therein, of a second circuit, a relay having a winding in said second circuit, means for changing the flow 30 of current in the line circuit, each change of current in said line circuit inducing a momentary flow of current in said second circuit, said relay responding to the currents induced in 35

said second circuit, a plurality of switches, means for associating said relay with the switches in succession, means for moving the associated switch on each operation of said relay, and means for holding the relay operated until the switch has made a complete movement.

10. The combination of a line circuit having a source of current therein, of a second circuit, a relay having a winding in said second circuit, means for changing the flow of current in said line circuit, the change of current in said line circuit inducing a flow of current in said second circuit for operating said relay, a step-by-step switch operated on each operation of said relay, and a differential winding for said relay rendered effective by 55 said switch for causing the relay to release.

11. The combination of a line, means to transmit impulses over said line, a line relay, means to maintain said relay operated during the sending of a series of impulses, and a second relay actuated in response to the inductive action of each impulse on said line relay.

12. The combination of a line, means to transmit impulses over said line, a relay connected to said line and arranged to remain energized during the sending of a series of impulses, a second relay actuated in response to the effect of said impulses on the first relay, a device arranged to take a setting in response to said second relay, and release means for said device controlled by said first relay.

In witness whereof, I hereunto subscribe my name this 19th day of June, A. D. 1922.

WALTER P. ALBERT.
